TIME CONTROL OF FUEL INJECTION FOR INTERNAL COMBUSTION ENGINES

Filed Nov. 30, 1926

INVENTOR

EDWARD L LOWE

BY

Frederick Louis & Robert
ATTORNEYS.

UNITED STATES PATENT OFFICE.

EDWARD L. LOWE, OF PALO ALTO, CALIFORNIA, ASSIGNOR TO J. W. CLUNE CO., OF LOS ANGELES, CALIFORNIA, A CORPORATION OF CALIFORNIA.

TIME CONTROL OF FUEL INJECTION FOR INTERNAL-COMBUSTION ENGINES.

Application filed November 30, 1926. Serial No. 151,638.

This invention, stated in its broadest terms, relates to the control of fuel injection to the burners of internal combustion engines as of the general type, such as for instance is disclosed in Letters Patent granted to me Nos. 1,443,187; 1,450,691; 1,462,514; and 1,454,972. In internal combustion engines of the character under consideration it is desirable and essential that efficient time control of fuel injection be provided.

The leading object of the present invention resides in the provision of novel means of time control of fuel injection which is of simple, practical, efficient, and comparatively inexpensive construction and in which the time control may be adjusted in such manner as to determine the injection of the fuel charge at any desired position of the piston reckoned from the upper end of its stroke and in detailed manner to be more fully set forth.

Other and further objects of the present invention reside in the provision of novel features of construction and arrangement and combination of parts for attaining the results sought by the leading object.

With these and other objects in view, the invention consists of the novel construction hereinafter described and finally claimed.

The nature, characteristic features and scope of the invention will be more fully understood from the following description taken in connection with the accompanying drawings forming part hereof, and in which:

Fig. 1, is a longitudinal section partly in elevation illustrating a time control of fuel injection embodying my invention.

Fig. 2, is a fragmentary view in vertical section of the cam operated parts coacting with the cams located at the right hand side of Fig. 1; and

Fig. 3, is a horizontal sectional view partly in elevation taken upon the line 3-3 of Fig. 2.

For the purpose of illustrating my invention I have shown in the accompanying drawings one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of the instrumentalities as herein shown and described.

Referring to the drawing, 1 designates housing members which rotatably support, as by ball bearings 2, a longitudinally arranged tubular shaft 3, which has mounted thereon as at the right hand end a pair of cams 4, best seen in Figs. 2 and 3, it being understood that said cams are positioned within the housing members 1. The cams 4 are arranged to coact with rollers 5, carried by pivotally supported members 6 for vertically reciprocating pump plungers 7. The parts 5, 6 and 7 are not shown in Fig. 1, but are clearly illustrated in Figs. 2 and 3. The purpose of the pump plunger 7 is to force the fuel to the burner (not shown).

It is the purpose and object of the present invention to effect the control or timing of the vertically reciprocating pump plungers 7 and the following description will be restricted to the timing mechanism which is of the essence of the present invention. Carried by the opposed ends of the hollow shafts 3 and arranged exteriorly with respect thereto and in concentric or telescoping relation therewith is a longitudinally arranged end-wise shiftable carrier shaft or member 8, which is relatively locked with respect to the hollow shafts 3 as by keys 9, so as to rotate with said shaft but said carrier shaft 8 is movable longitudinally with respect to said shafts 3, by reason of the slotted portions 10, as clearly shown in Fig. 1. This key in slotted arrangement is what is known as a Woodruff key. The central portion of the carrier shaft 8 is solid as at 11. Extending from the intermediate and left hand members 1, are tubular members 12 which are rigidly connected thereto and which carry a centrally arranged two-part housing 13, said housing sections being clamped together by bolts 14 and having screw-threaded relation as at 15 with the members 12, so that access may be readily had to the interior of the housing 13. Carried by the solid part 11 of the carrier shaft 8 is a spiral gear 16 in mesh with a companion gear 17 carried by a shaft 18, motion to which is imparted from the engine shaft so that it has a continuous rotary movement therewith. This continuous rotary movement is in turn imparted to the hollow shaft 3, so that the cams 4 are continuously reciprocating the pump pistons or plungers 7. In the operation of internal combustion engines under conditions of varying load and speed, it is essential that means be provided for

varying, under control, the instant of full injection relative to the position of the piston reckoned from the upper end of its stroke. This is in every way analogous to the so-called advance and retard of the spark in engines using electric spark ignition. For this purpose the construction above described has been provided and it is apparent that such desired timing relation between the operation of the cams 4 and the position of the pistons of the engine connected as they are and moving synchronously as they do with the shaft 18, may be controlled and varied as desired by causing the gear 16 to be shifted so as to engage with different longitudinal parts of the gear 17. This I accomplish by shifting end-wise the carrier shaft 8 with respect to the hollow shafts 3 by means of a push and pull rod 19 fixed to the solid part 11 of the carrier shaft 8 by means of a screwed connection and transverse pin 20, which passes through the parts 11 and 19. This rod 19 may be moved longitudinally either by hand or automatically through the instrumentality of a yoke or forked member 21, see the right hand side of Fig. 1. As the rod 19 and its hollow shaft 3 and carrier shaft 8 are shifted to the left or to the right, it is apparent that air compression may occur between the housing sections 13 and the chambers 22 adjacent the solid body portion 11, and therefore air vents 23 are provided.

To recapitulate, it is clear that the desired varying time relation between the movements of the shaft 18 and carrier shaft 8 may be effected by causing the spiral gear 16 to engage with different longitudinal parts of the companion spiral gear 17. In this manner the fuel charge may be introduced at will over a range of pump piston or plunger movement varying from a little in advance of reaching dead centre to dead centre and as far beyond dead centre as may be desired, the object of the above described operation being analogous to the advance and retard of spark in the ordinary explosion engine.

It will be understood that the pump pistons or plungers as 7 force the fuel to a burner (not shown) and the time of fuel injection relative to the position of the piston as seen in Fig. 2 will evidently be determined by the time when the point of the cam 4 engages the roller 5 relative to the position of the engine piston 7.

It will now be apparent that I have devised a novel and useful construction of time control of fuel injection for internal combustion engines which embodies the features of advantage enumerated as desirable in the statement of the invention and the above description and while I have in the present instance shown and described the preferred embodiment thereof which has been found in practice to give satisfactory and reliable results, it is to be understood that the same is sus-

ceptible of modification in various particulars without departing from the spirit or scope of the invention or sacrificing any of its advantages.

Having thus described my invention what I claim as new and desire to secure by Letters Patent, is:

1. In a timing control of the character stated, a hollow cam shaft, a cam mounted upon said shaft, a sleeve movable longitudinally of said cam shaft, a spiral gear fixed thereto, a constantly operating shaft actuated from the engine shaft, a spiral gear thereon for meshing with said first mentioned spiral gear, and a pull rod extending within said hollow shaft for moving said first mentioned spiral gear with respect to said second gear for changing the timing of said cam shaft.

2. In a timing control of the character stated, a cam actuated pump piston, a hollow cam shaft, a cam mounted upon said shaft for actuating said piston, rollers intermediate said piston and said cam, a rod movable longitudinally within said cam shaft, a spiral gear fixed thereto, a constantly operating shaft, a spiral gear thereon for meshing with said first mentioned spiral gear, and means connected to said rod for moving said first mentioned spiral gear with respect to said second gear for changing the timing of said cam shaft.

3. In a timing control of the character stated, a cam actuated pump piston, a horizontally arranged hollow cam shaft, a cam mounted upon said shaft for actuating said piston, pivotally mounted rollers intermediate said piston and said cam, a carrier shaft keyed to rotate with but movable longitudinally of said cam shaft, a spiral gear fixed thereto, a constantly operating shaft, a spiral gear thereon for meshing with said first mentioned spiral gear and means within said hollow shaft for moving said first mentioned spiral gear with respect to said second gear for changing the timing of said cam shaft.

4. In a timing control of the character stated, a cam actuated pump piston, a housing therefor, a horizontally arranged cam shaft, a cam mounted upon said shaft for actuating said piston, a member movable longitudinally of said cam shaft, a spiral gear fixed thereto, a constantly operating shaft, a spiral gear thereon for meshing with said first mentioned spiral gear, and means within said cam shaft for moving said first mentioned spiral gear with respect to said second gear for changing the timing of said cam shaft.

5. In a timing control of the character stated, a cam actuated pump piston, a horizontally arranged cam shaft, a cam mounted upon said shaft for actuating said piston, a member movable longitudinally of said cam shaft, said member having a central portion

provided with air ports communicating with said housing, a spiral gear fixed thereto, a constantly operating shaft, and a spiral gear thereon for meshing with said first mentioned spiral gear with respect to said second gear for changing the timing of said cam shaft. 15

6. In a timing control of the character stated, a cam actuated pump piston, a horizontally arranged cam shaft, a cam mounted upon said shaft for actuating said valve stem, a carrier shaft movable longitudinally of said cam shaft, said carrier shaft having a central 10

portion provided with air ports communicating with said housing, a spiral gear fixed thereto, a constantly operating shaft, a spiral gear thereon for meshing with said first mentioned spiral gear, means for moving said first mentioned spiral gear with respect to said second gear for changing the timing of 20 said cam shaft, and a transverse pin common to said central portion and the inner end of said gear shifting means for securing said parts together.

EDWARD L. LOWE.
